UNITED STATES PATENT OFFICE.

WILLIAM TEMPLIN, OF GLENELLYN, ILLINOIS.

MEANS FOR FASTENING BOOKS TO STANDS.

1,077,896.

Specification of Letters Patent. Patented Nov. 4, 1913.

Application filed August 17, 1912. Serial No. 715,569.

To all whom it may concern:

Be it known that I, WILLIAM TEMPLIN, a citizen of the United States, residing at Glenellyn, in the county of DuPage and 5 State of Illinois, have invented certain new and useful Means for Fastening Books to Stands, of which the following is a specification.

This invention relates to the arrangement 10 of a stand or support with means for fastening or locking a book thereto, the book being provided with separate locking or holding devices adapted to co-act with the locking or holding devices of the stand.

15 The objects of this invention may be best understood when considered in connection with one of the uses for which it is intended. Manufacturers, for instance manufacturers of clothing, frequently send out many 20 comparatively large and expensive sample books to dealers throughout the country and it is very desirable that such books shall be kept on display or ready for convenient reference. For this reason the manufacturer may furnish a stand for the book. If such stand is 25 of ordinary construction, the dealer may use it for other purposes or may use it for supporting the book of some other manufacturer.

30 Among the objects of this invention are to provide a stand and book with co-acting fastening devices whereby the stand will not readily support any book, except the ones intended therefor; to provide an arrangement 35 whereby the book will ordinarily be supported in open position; and to provide such other advantages as will appear hereinafter.

In the accompanying drawings illustrating 40 my invention, Figure 1 is a front view of stand and book with parts broken away to show structural features; Fig. 2 is a side view of the same; Figs. 3 and 4 are details of one form of locking or fastening member 45 for the book cover; Figs. 5 and 6 are details showing another method of fastening the book to the stand; and Figs. 7 and 8 are details showing a still further modification of the book holding or locking device.

50 As indicated in these drawings, 9 represents a stand of any suitable construction, preferably one having relatively open or skeleton work top 10, formed of bar iron or metal as indicated. This top is preferably 55 slanted at a convenient angle for inspection of the book placed thereon and such slant

serves a further purpose in that any book not provided with suitable fastening means will tend to slide off therefrom. This slanting of the top furthermore insures the more 60 secure holding of a book which is provided with suitable holding means. A preferred form of such holding means comprises short chains or flexible members 11 which are secured to the upper strip of the top 10, and 65 which are provided with hooks 12. The book 13, which for convenience is shown with the leaves omitted, has its covers 14 provided with slots or openings 15, and across these openings are secured short bars or holding 70 members 16, these bars being provided with large ends 17 for receiving rivets 18 for holding them to the cover boards. These holding members 16 are so positioned as to be readily engaged by the hooks 12 which 75 hooks pass through the slots or perforations 15. The stand top 10 is preferably made somewhat smaller than the book so that when the hooks 12 are engaged with the fastening devices 15, the book will be 80 supported in about the position shown in Figs. 1 and 2, and will be properly balanced on the stand. It will be noted that the turning of the leaves of these books, which frequently are relatively heavy and may 85 carry samples of goods, may tend to shift the book longitudinally of the stand, but with my improved fastening devices, the book will be securely held from movement in such direction while at the same time the 90 flexible fastening devices permit the leaves to be readily turned. These books may be sent out either with or without the stands and in order to avoid the defacement of the cover by the fastening device 16, I prefer to 95 attach this device directly to the cover board as indicated in Figs. 3 and 4 before the end sheet 19 or the outside cover 20 is applied to the board. The fastening device 16 may be countersunk or let into the board so as to 100 leave a smooth surface if desired. After the covering sheets have been applied to the cover board all that is necessary in order to prepare the same for use is to cut out the small portions of such sheets opposite the 105 opening 15.

It will be readily observed that by arranging the chains and hooks at different points on the frame or stand 10 and placing the fastening devices 16 at corresponding 110 points on the books to go with such stands, different combinations may be made so that

the books of one manufacturer can not be readily substituted and held in position on the stand of another manufacturer. It will also be observed that various forms of fastening devices will readily suggest themselves, as coming within the scope of this invention. For instance, as shown in Figs. 5 and 6, the chain 21 is secured to the lower cross member of the frame and has a bent 10 clip 22 secured to its opposite end. This clip is provided with an opening 23 which is adapted to fit over a catch 24 secured to the book cover 25. The catch is so arranged that after the clip 22 has been engaged therewith 15 it will hold the upper ends of the clip securely in position while the lower edge of the book cover 25 rests against the downwardly extending portion of the clip. Another slight modification is shown in Figs. 7 20 and 8 in which the chain or flexible member 26 is secured to a bent metallic strip 27

having a slot 28 in its free end. This slotted end engages with a catch 29 secured to the book cover 30, the book being held substantially the same as in the arrangement just described. In either case the fastening device is such as to prevent too great longitudinal movement of the book on the stand. 25

Having thus described my invention, what I claim and desire to secure by Letters Patent is:

The combination of a stand having a downwardly sloping top, flexible members secured to said top, hooks or the like at the ends of said members, a book having slots through the cover thereof, and engaging 35 devices extending across said slots for engagement with said hooks.

WILLIAM TEMPLIN.
